UNITED STATES PATENT OFFICE.

HOWARD H. McGEE, OF NEW YORK, N. Y.

CLOSURE.

Application filed June 1, 1926. Serial No. 113,004.

This invention relates to a novel and improved closure particularly adapted to control the passage of a fluid through a flexible casing such as a rubber tube. The invention 5 may be employed in a variety of locations, but for the purposes of illustration I shall describe it as used with a syringe or hot water bag, this being the situation in which the invention finds particular utility.

10 The principal object of my invention is to provide a valve which may be employed in connection with a flexible casing and actuated by pressure exerted longitudinally of the casing. Valves of known construction are 15 usually operated by handles or else if they are automatic in construction they require a separate spring element and other complicated structure to insure their operation. According to my invention I so construct the 20 casing in which the valve is disposed that a portion of the casing will give the desired spring action, thus eliminating the separate spring elements which have been found necessary in the prior art constructions.

25 A further object of my invention is to provide a valve which may be used in connection with a syringe or the like and which may be operated solely by pressure exerted longitudinally thereof, this pressure being 30 exerted by contact of the structure with some part of the body of the user.

The invention will be best understood by referring to the accompanying drawing in which I have shown selected embodiments of 35 my invention, and in which

Figure 1 shows one form of my invention as applied to a syringe bag.

Figure 2 is a longitudinal section through the invention, as shown in Figure 1, and upon 40 an enlarged scale, the valve being shown closed.

Figure 3 is a view similar to Figure 2 but showing the valve opened.

Figure 4 is a view similar to Figure 1 but 45 showing a different form of my invention, this form being applied to an ordinary water bag.

Figure 5 is a longitudinal view through the invention, as shown in Figure 4, and on 50 an enlarged scale, the valve being shown closed.

Figure 6 is a view corresponding to Figure 5 but showing the valve opened.

Figure 7 is a perspective view of the valve 55 shown in Figures 2, 3, 5 and 6.

Referring now to Figures 1, 2 and 3, the

numeral 1 designates a syringe bag of ordinary form to which, for the purposes of illustration, I have shown my invention as being applied. The numeral 2 designates the 60 discharge nozzle, which may be of usual form and which is connected to the bag 1 by means of a flexible tube 3, as is well known in the art. Disposed between the tube 3 and nozzle 2 is a casing 4 which may conveniently 65 be of one piece of rubber and which comprises a chamber 5 having flexible and resilient walls 15 and 17 for a purpose which will presently appear.

The casing 4 is provided adjacent one end 70 with a longitudinal bore 6 terminating in a valve chamber 7 which in turn is connected with the chamber 5 by the bore 8. The chamber 5 terminates in a socket 9 which receives the nozzle 2 in the usual and well 75 known manner. Received within the bore 8 is the valve-stem 10 having the valve-head 11 disposed within the valve chamber 7, the valve seat 12 being formed as part of the wall of the chamber. The valve also 80 comprises a foot 13 which is preferably of the concavo-convex form shown and has its opposite edges 14 contacting with the upper wall 15 of the chamber 5. The foot has the sides 16 cut away to permit the passage of 85 fluid thereby, although other suitable means may be provided for the same purpose.

The body of the casing 4 is relatively 90 rigid, whereas the walls 15 and 17 of the chamber 5 are relatively flexible and resilient, and the latter normally occupy the position shown in Figure 2, wherein the valve is maintained in closed position by engagement between the wall 15 and the edges 14 of the foot 13. The opening of the valve 95 is effected by pressure applied to the foot or anchor 13 either by moving pipe 2 longitudinally and thereby moving wall 17 into pressing contact with the foot 13, or by applying the pressure directly to wall 17. In 100 either case, the walls 17 and 15 will be deformed from the position shown in Fig. 2 to that shown in Fig. 3. The valve will remain open so long as the pressure is maintained against the foot 13. When the pressure is removed, wall 15, by reason of its 105 elasticity, will restore the valve to its normal closed position. The edges 14 of the foot still contact with the upper wall 15 of the chamber 5 and fluid may pass freely 110 through the bore 8 into the chamber 5 and thus into the nozzle 2. Passage by the foot

13 is permitted because of the cut away sides 16 thereof. It will be noted that the valve is independent of, that is, unattached to, the casing, and is movable longitudinally therein. Also, that the edges 14 of the member 13 are always in engagement with the flexible and resilient wall 15 so that the pressure thereof on such edges will immediately effect a closing of the valve when the pressure 10 which caused the opening of the valve is removed.

Referring now to the embodiment shown in Figures 4, 5 and 6, the numeral 18 designates a water bag of usual form, to which is applied my invention in the form of a casing 19, preferably made of one piece of material and which, if desired, may be made integral with the bag, as shown. In this form the same type of valve is employed 20 as in the other embodiment, this valve having the head 11, stem 10 and foot 13, the neck 10 being disposed within a bore 20 in the casing. The portion 21 of the casing is relatively rigid, and secured to the lower 25 end thereof is a relatively flexible diaphragm 22 forming the upper wall of the chamber 23 which has the relatively rigid lower wall 24. The chamber 23 terminates in a bore 25 forming a nozzle, through 30 which a liquid may be poured into the bag or discharged therefrom. In using this form of my invention pressure is applied longitudinally to the nozzle as in the other embodiment, and this pressure causes the 35 various parts to change from the relation shown in Figure 5 to the relation shown in Figure 6. When in the position shown in Figure 5 the resilient wall 22 will hold the foot of the valve in the position shown, thus 40 resiliently holding the head 11 upon the seat 12'. However, when pressure is exerted longitudinally of the casing the diaphragm 22 will snap from the position shown in Figure 5 to that shown in Figure 6. This snap 45 action is important in that it gives a quick, positive movement to the valve causing an abrupt opening or closing thereof. The bottom wall 24 of the chamber 23 will then engage the foot 13 and open the valve, in a 50 manner similar to that described in connection with the embodiment of Figures 1, 2 and 3. When the parts are in the positions shown in Figure 6, fluid may pass freely 55 into the bag 18 or may be discharged therefrom.

From the above it will be apparent that I have devised a closure which is of extremely simple construction and in which the number of elements has been reduced to a minimum. The operation of the device is as simple as is its construction, all that is necessary being an application of the necessary force longitudinally of the valve structure. In the use of my invention shown in Figures 4, 5 and 6 a hot water bag, for example, may

be filled, the parts for this purpose being moved to position as shown in Figure 6, in which position they will remain. When it is desired to close the valve all that is necessary is to pull the nozzle 25 away from the bag, when the diaphragm 22 will snap the valve to the position shown in Figure 5. The valve shown in this embodiment must be either closed or open; the diaphragm 22 cannot occupy an intermediate position because of its construction as a part of a sphere.

When my invention is employed with a syringe such as shown in Figures 1, 2 and 3 the necessary pressure may be exerted with the fingers or by contact of the wall 17 of the casing with another part of the user's body. This does away with any annoyance arising from the use of a separate valve. The cessation of flow of the liquid through the nozzle will be instantaneous and dependent solely upon the release of pressure.

While I have shown one form of my invention as applied to a syringe bag and another form as applied to a water bag, it is obvious that either form may be put to either use and it is also obvious that both forms are adapted to a variety of uses, those shown and described being merely illustrative.

I am aware that various changes in details may be made within the scope of my invention and I, therefore, do not intend to limit myself except by the appended claims.

I claim:

1. A closure comprising a casing having a chamber with a valve seat, and a valve independent of the casing and movable longitudinally therein, a part of the wall of said casing being flexible and resilient and adapted to bear against the valve to hold it in a given position.

2. A closure comprising a casing having a relatively rigid section forming a valve seat, a relatively flexible and resilient section, and a valve independent of the casing and movable therein, said flexible and resilient section adapted to bear against the valve to hold it in a given position.

3. A closure comprising a casing having an unattached valve therein, and having also a flexible and resilient portion adapted to bear against the valve to hold it in a given position, but permit movement thereof upon application of longitudinal pressure to the casing.

4. A closure comprising a casing having a valve chamber, a valve unattached to the casing and coacting with a seat in said chamber, a second chamber having a flexible and resilient wall, the valve stem being disposed in said second chamber and engaging said wall, the resiliency of said wall being adapted to maintain said valve in a given position.

5. A closure comprising a casing having a chamber with a valve seat, and a valve independent of the casing and movable therein into seated and unseated positions, 5 the wall of the casing normally shaped to hold the valve seated, and capable of manipulation to unseat the valve.
6. A closure comprising a casing having two chambers, a valve independent of the 10 casing and movable longitudinally therein and having its head in one and its stem extending into the other of said chambers, the latter of said chambers having a flexible and resilient wall adapted to engage the 15 valve stem whereby, upon the application of longitudinal pressure to the casing, the valve will be opened and upon the release of such pressure the valve will be closed.
7. A closure comprising a casing having 20 inlet and outlet openings and a valve chamber, a valve in said chamber, said valve being independent of the casing and movable longitudinally therein, said casing comprising a second chamber having flexible and 25 resilient walls and into which chamber the stem of said valve extends, whereby longi-
- tudinal pressure applied to the casing will deform said walls to effect the opening and closing of the valve.
8. A closure comprising a casing having 30 two chambers in one of which is a valve seat, a valve independent of the casing and movable longitudinally therein and having its stem extending into the other of said chambers, the walls of said other chamber 35 being flexible and resilient to permit movement thereof and thereby movement of the valve toward and away from its seat upon the application of longitudinal pressure to the casing. 40
9. A closure comprising a casing having a flexible and resilient section, a valve within but unattached to the casing and movable longitudinally therein, said section adapted to bear upon said valve to hold it in 45 a given position but permitting it to be moved from said position upon the application of longitudinal pressure to the casing.

In testimony whereof, I have affixed my signature to this specification.

HOWARD H. McGEE.
